DESIGN FOR A VEHICLE ORNAMENT OR SIMILAR ARTICLE

Werner H. A. Gubitz, Detroit, Mich., assignor to
Packard Motor Car Company, Detroit, Mich., a
corporation of Michigan

Application May 27, 1935, Serial No. 57,040

Term of patent 14 years

To all whom it may concern:

Be it known that I, Werner H. A. Gubitz, a citizen of the United States, residing at Detroit, county of Wayne, State of Michigan, have invented a new, original, and ornamental Design for a Vehicle Ornament or Similar Article, of which the following is a specification, reference being had to the accompanying drawing, forming a part thereof, and in which:

Fig. 1 is an elevation of one side of an ornament incorporating my new design with the base portion broken away;

Fig. 2 is a plan view of the ornament with the base portion broken away;

Fig. 3 is an elevation in the opposite side of

the ornament from that shown in Fig. 1 with the base portion broken away.

The principal and dominating features of my design reside in the rearwardly extending wing-like cape element substantially triangular in outline both in side elevation and top plan views and the representation of long flowing hair lying over and merging into the top of the extended cape element.

I claim:

The ornamental design for a vehicle ornament or similar article, as shown and described.

In testimony whereof I affix my signature.

WERNER H. A. GUBITZ.
